UNITED STATES PATENT OFFICE.

LOUIS W. CHISM, OF SOUTHBURG, CONNECTICUT, ASSIGNOR, BY MESNE ASSIGNMENTS, TO THE STEEL PRODUCTS COMPANY, OF HARTFORD, CONNECTICUT, A CORPORATION OF CONNECTICUT.

CARRIER FOR STORE-SERVICE.

1,289,393.

Specification of Letters Patent. Patented Dec. 31, 1918.

Application filed April 23, 1917. Serial No. 163,794.

To all whom it may concern:

Be it known that I, LOUIS W. CHISM, a citizen of the United States, and a resident of Southington, in the county of Hartford, 5 and State of Connecticut, have invented an Improvement in Carriers for Store-Service, of which the following description, in connection with the accompanying drawings, is a specification, like characters on the drawings representing like parts.

This invention relates to cash carriers for store service, and is more particularly concerned with cover locking and unlocking means. My invention will be best understood by reference to the following description, when taken in connection with the accompanying drawings of one specific embodiment thereof, while its scope will be more particularly pointed out in the appended claims.

In the drawings:

Figure 1 is a plan of a cash carrier embodying my invention;

Fig. 2 is a side elevation of the same;

Fig. 3 is an end elevation of the same, partly in cross section, on line 3—3 of Fig. 1, showing the cover closed and locked; and

Fig. 4 is a view similar to Fig. 3, but showing in full lines the cover unlocked, and 30 in dotted lines the cover opened.

Referring to the drawings, and to the embodiment of my invention which I have selected for illustration, I have there shown a cash carrier which in many respects is similar to a well known-type of carrier in common use in connection with store service systems of the cable propulsion type, the same comprising a receptacle 5 to contain the cash sales slips or other articles. In the 35 type of carrier selected for exemplification, this receptacle is mounted on a base 6, provided with suitable guideways 7 to receive the rails of the tracks. Grippers 8 and 9 operate in a usual and well-known manner 40 to grip the carrier propelling cable to propel the carrier along the tracks.

In the use of all cash carriers of this general type with which I am familiar, much difficulty has heretofore been experienced 45 owing to the fact that the cover of a carrier

will sometimes open accidentally when the carrier is in transit, or under other circumstances. It occasionally happens that one carrier strikes another end to end, or that a carrier strikes end on against a buffer or 55 some other stationary object, which tends to stop it. Under such circumstances, the body of the receptacle is apt to spring and become distorted momentarily to a sufficient extent to release the locking device, and thus permit the cover to open under the influence of its spring. In many of such carriers with 60 which I am familiar, the locking devices in common use are more or less unsatisfactory for the further reason that the operation of 65 locking and unlocking the cover is slow and inconvenient. In the carrier which forms the subject matter of my present invention, these and many other objectionable features are eliminated by the cover and cover-locking 70 devices which I will now describe.

The usual opening of the receptacle is provided with a cover or closure 10, preferably inclosed by the surrounding walls of the receptacle 5 and hinged thereto by means 75 of a hinge-pin or pintle 11, the latter being encircled by the usual spring 12, which constantly tends to open the cover in a well-known manner. In cash carriers of this 80 type, the cover is usually provided with some sort of locking device, which depends upon engagement with a lip or slot facing inwardly with relation to the wall of the receptacle. Carriers so constructed are subject to the accidental opening to which I 85 have alluded. The reason for this will be appreciated when it is understood that the striking of such carrier on its end tends to increase the width of the body of the receptacle, and unless the locking lip or slot is of 90 considerable depth, the momentary distortion of the receptacle is apt to cause the cover to fly open.

In the carrier herein shown, however, the receptacle 5 is provided with a locking lip or lug 13, which faces in an outward direction, while the cover carries a co-operating lip or lug 14 which faces inwardly, as will be understood from an inspection of Figs. 3 and 4. Thus it is apparent that any distortion of 100

the receptacle tending to increase the width of the latter simply serves to engage the locking device all the more firmly, instead of tending to unlock it.

5 The lip 14 carried by the cover 10 may be operated by any appropriate means, but herein, instead of employing a separate and distinct locking lever or other independent lock operating instrumentality, I provide 10 the cover 10 itself with an integral lock-operating device. In the present instance, this is accomplished by making the cover, or at least a considerable portion intermediate its opposite edges, comparatively thin and 15 resilient, so that it shall be susceptible of distortion by the hand of the operator to unlock the cover and permit the same to open under the influence of its spring. In the present example, the cover is provided with 20 a buckling portion 15 having a normal bias toward the closure locking position which is illustrated in Fig. 3, and having provision whereby it may be buckled in an opposite direction to unlock the closure. Thus it will 25 be seen that the closure has provision for expansion and contraction in the direction of its width, or in other words, it is expandible and contractible in a plane connecting the locking means with the axis of the cover. 30 This will be evident from an inspection of Figs. 3 and 4.

A quick, forcible depression of the buckled portion 15 by the thumb or fingers of the operator at the point A serves to carry 35 such portion inward or downward past the plane of the marginal portion of the cover to some such position as that illustrated in Fig. 4, thus increasing the width of the cover to a sufficient extent to cause the lip 40 14 to move in an outward direction with relation to the lip 13, and to release therefrom, whereupon the spring 12 will instantly open the cover. The sudden stopping of the latter will naturally cause the buckling portion 45 to resume its initial position with relation to the marginal portion of the cover, ready for the next closing movement, but should it happen that such restoration does not occur automatically, the operator can readily buckle the cover in the opposite direction. The 50 locking of the cover is accomplished automatically by simply closing the same by suitable pressure at the point B, it being understood that the lips 13 and 14 are slightly 55 beveled as illustrated in Figs. 3 and 4, so that one will snap past the other into the position shown in Fig. 3. By this means, the cover is provided with a locking device which is secure against accidental unlocking 60 due to the distortion hereinbefore referred to, and the locking and unlocking are effected quickly and conveniently without the use of a separate locking device.

While I have herein shown and described

one specific embodiment of my invention for 65 illustrative purposes, and have disclosed and discussed in detail the construction and arrangement incidental to one specific application thereof, it is to be understood that the invention is limited neither to the mere details 70 or relative arrangement of parts, nor to its specific embodiment herein shown, but that extensive deviations from the illustrated form or embodiment of the invention may be made, without departing from the 75 principles thereof.

Having thus described my invention, what I claim and desire by Letters Patent to secure is:

1. A container comprising a body having 80 a catch and a cover hinged thereto having a hook extending outwardly from the edge thereof, said cover having a portion resiliently bowed between the hinge and hook.

2. In a cash carrier for store service, the 85 combination of a receptacle and a hinged closure therefor having means tending to open the same when released, said receptacle and said closure having coöperating means normally locking said closure in its closed 90 position and having provision automatically to lock the same consequent upon closing movement, said closure having a portion which is extensible and contractible in a plane connecting the locking means with the 95 axis of said closure, whereby said locking means may be operated by extension and contraction in said plane.

3. In a cash carrier for store service, the 100 combination of a receptacle and a hinged closure therefor having means tending to open the same when released, said receptacle and said closure having coöperating means normally locking said closure in its closed position and having provision automatically 105 to lock the same consequent upon closing movement, said closure being provided with a buckling portion having a normal bias toward a closure locking position and having provision whereby it may be buckled in an 110 opposite direction to unlock said closure.

4. In a cash carrier for store service, the 115 combination of a receptacle and a closure therefor, said closure being hinged at one edge thereof to said receptacle, said closure and said receptacle having coöperating locking means at the opposite edge of said closure, said closure having intermediate said edges a resilient buckled portion providing for expansion and contraction of the width 120 of said cover between the hinge and locking means, said buckled portion having a normal bias toward a closure-locking position.

5. A container comprising a body having a catch and a hinged cover comprising a 125 sheet adapted to close within the mouth of the body and having a marginal hook-like extension adapted to extend past the pe-

riphery of said body and engage the catch from the exterior, said sheet being resiliently bowed between the hinge and the hook.

6. In a cash carrier for store service, the combination of a receptacle and a hinged closure therefor having its edge disposed for the most part within the inner edge of said receptacle, said receptacle and said closure

being provided with coöperating locking means including an outwardly facing part 10 on said receptacle and an inwardly facing part on said closure.

In testimony whereof, I have signed my name to this specification.

LOUIS W. CHISM.
